UNITED STATES PATENT OFFICE.

EDWARD B. JACOBSON, OF PITTSFIELD, MASSACHUSETTS, ASSIGNOR TO THE PITTSFIELD SPARK COIL COMPANY, OF PITTSFIELD, MASSACHUSETTS, A CORPORATION OF MASSACHUSETTS.

BRUSH AND BRUSH-HOLDER FOR MAGNETO-ELECTRIC MACHINES.

SPECIFICATION forming part of Letters Patent No. 770,175, dated September 13, 1904.

Application filed August 20, 1903. Serial No. 170,167. (No model.)

To all whom it may concern:

Be it known that I, EDWARD B. JACOBSON, a citizen of the United States, residing at Pittsfield, in the county of Berkshire, State of Massachusetts, have invented a certain new and useful Improvement in Brushes and Brush-Holders for Magneto-Electric Machines, of which the following is a specification, reference being had therein to the accompanying drawings.

The invention consists more particularly in brushes and brush-holders for magneto-electric machines.

Various special aims or objects of different features of the invention are indicated in the course of the following description.

I have shown in the accompanying drawings the invention in the best form of embodiment which I have thus far devised.

In the drawings, Figure 1 is a partly-sectional elevation of one end of a dynamo having my invention applied thereto. Fig. 2 is a view in section along the line 2 2 of Fig. 1. Fig. 3 is a partly-sectional view illustrating the manner of mounting the brush-holders 9 9. Fig. 4 shows in plan, partly broken away and in vertical cross-section, one of the brushes.

Having reference to the drawings, 1 designates part of the casing of a dynamo; 4, one of the field-coils; 3, the armature; 6, the commutator, and 7 the shaft on which the armature and commutator are mounted.

8 8 are the commutator-brushes. The said brushes are contained in tubular cylindrical brush-holders 9 9, which latter are mounted in fixed position upon the transverse web 10, forming part of the casing. The brushes are pressed against the surface of the commutator by means of spring-actuated presser-arms 11 11, which latter act to take up the wear of the brushes. One of the brushes is shown separately in plan, partly broken away and in vertical cross-section, in Fig. 4 of the drawings. It comprises, essentially, a central core, as 81, of fine wire-gauze wound spirally into a cylindrical coil, a cylindrical body or pencil 82, of pressed or tempered graphite, con-

taining the said core, and a shell 83, of brass. The employment of the wire-gauze core insures perfect contact with the commutator, the graphite serving to lubricate the contacting surface of the commutator, while the brass shell protects the graphite and holds the latter in compact form and also insures perfect electrical contact between the brush and the brush-holder. The presser-arm 11, which operates with each brush 8, is supported by a pivotal stud 111 and is acted upon by a spring 112, the free extremity of which latter bears against a projection 113 on the outer side of the presser-arm, the said spring tending to move the presser-arm in a direction to press the corresponding brush radially inward against the periphery of the commutator.

For the purpose of enabling the tension of the spring 112 of each presser-arm to be adjusted so as to vary as desired the force with which the brush is pushed into contact with the commutator a hub 114, having upon its outer end a flange 115 and a circular series of projections 116, is fitted upon the corresponding stud 111 with capacity to turn thereon. The presser-arm 11 is sleeved upon the exterior of this hub, so as to turn freely thereon. Within a hole in the outer end of the stud 111 is fixed a pin 117, the opposite ends of the said pin projecting on opposite sides of the said stud and being adapted to enter between adjacent projections of the series of projections 116. The hub is chambered at its inner side to receive an expanding spiral spring 118, which is compressed between the interior shoulder of the hub and the adjacent collar or washer 119 next the fixed support of the stud, the said spring acting with a tendency to hold the said hub pressed outwardly upon the stud, with certain of the projections 116 in engagement with the pin 117. A coil or spiral forming portion of the spring 112 encircles the hub 114 between the flange 115 and the arm 11, and the corresponding end of the spring is engaged with the hub. It will be perceived that the hub constitutes a support for the coil portion of the spring and an abutment from which the spring reacts in

pressing against the projection 113 of the presser-arm 11. The engagement of the pin 117 with the projections 116 of the hub prevents the hub from turning under the influence of the tension of the spring. If, however, it is desired to adjust the said tension, this may be accomplished by pressing the hub inwardly along the stud 111, so as to compress the spring 118, and far enough to disengage the projections 116 from the pin 117, and then turning the hub in either direction as may be required in order to increase or diminish the tension to the required degree, after which on relieving the lateral pressure 15 against the hub and permitting the spring 118 to press it outwardly again the projections 116 thereof will reengage with the pin 117, carried by the stud 111, and lock the hub in its position of adjustment.

20 The free extremity of each presser-arm 11 works within vertical slots 91 91, which are formed through the upper and lower sides of the corresponding brush-holder. By the walls of the said slots the presser-arm is held in proper position and guided in its movements. By contact with the periphery of the commutator the inner or working end of the brush becomes worn in concave shape, fitting the said periphery, thereby furnishing the largest 25 contact-surface and diminishing the resistance and consequent sparking. For the purpose of preventing the brush from turning within the brush-holder, so that its concave face will no longer fit fully against the commutator, 30 which would diminish the extent of the surface-making contact with the commutator, the outer end of the brush is notched or slotted, as at 84, for a short portion of its length, and within the notch or slot is received the presser-arm. The engagement of the presser-arm 35 with the sides or walls of the said notch or slot holds the brush from turning. For the purpose of enabling the brush to be removed from the brush-holder a longitudinal slot 92 is formed in the outer side of the brush-holder. 40 Through this slot the point of a suitable tool may be inserted into engagement with the brush, and by movement of the said tool inward along the slot the brush may be pushed 45 radially inward out of the brush-holder.

50 The brush-holders and also the presser-arms are insulated from the web 10 in manner which I will presently describe. In order to obviate necessity for causing the current to flow from the brush through the presser-arm itself and also through the spring 112, which actuates such arm, the stud 111, on which the presser-arm is mounted, is itself placed in direct electrical communication with the adjacent brush-holder through the medium of a plate 12, to which the brush-holder and the said stud are applied and with which they are in electrical contact. The plate 12 itself is insulated from the web 10 by means of a sheet 55 121, Fig. 2, of vulcanized fiber or other suit-

able material, the fastenings by which the parts are united together being suitably insulated from the web 10. The inner end of the stud 111 is extended through a transverse hole in the web 10, and this hole is bushed 70 with insulating material, as also shown in Fig. 2. The said inner end of the stud is screw-threaded and receives a nut 13, which is insulated from the web by a suitable washer, as shown. Were the spring 112 included in 75 the circuit, it would tend to become heated during the operation of the dynamo, and the result of the heating would be to destroy its temper, rendering it useless or inefficient.

80 While I have been particular to describe the invention in the best form of embodiment which I have thus far devised, it is of course evident that various modifications in construction, arrangement, &c., may be made within the spirit of my invention.

85 From the respective studs 111 111 wires 14 14 extend within the casing to and connecting with the binding-posts 15 15, which latter project from the exterior of the said casing. To the said binding-posts in practice are connected the main conducting-wires.

I claim as my invention—

1. The improved commutator-brush, comprising, essentially, the core of wire-gauze wound into spiral form, the body or pencil of 95 graphite, and the inclosing metal shell, substantially as described.

2. The combination with the commutator, the brush, and the brush-holder, of the presser-arm, the spring for actuating the said presser-arm, the adjustable hub having the series of 100 projections on the outer end thereof, the pivotal stud, and the locking-pin on said stud engaging with the said projections to lock the hub in the desired position of adjustment.

105 3. The combination with the commutator, the brush, and the brush-holder, of the presser-arm, the spring for actuating the said presser-arm, the adjustable hub, the spring acting to press the said hub transversely, the pivotal 110 stud, and the locking-pin on said stud engaging with the said hub to lock the same in the desired position of adjustment, substantially as described.

115 4. The combination with the commutator, the brush, and the brush-holder, of the presser-arm, its actuating-spring, and the pivotal mounting for the said arm, of an insulated support in common for the said brush-holder and pivotal mounting serving to connect the two electrically and extraneously of the said 120 spring, substantially as described.

125 5. The combination with the brush having the slotted end, of the brush-holder having the slotted wall or shell, the presser-arm working in the slot of the said wall or shell and guided thereby, and also entering the slot of the brush to prevent the brush from turning, and means for operating the said presser-arm, substantially as described.

6. The combination with the brush having the slotted end, of the presser-arm entering the slot to prevent the brush from turning, and means for operating the said presser-arm, substantially as described.

7. The combination with the brush having the slotted end, of the brush-holder having the slotted wall or shell, the presser-arm working in the slot of the said wall or shell and guided thereby, and also entering the

slot of the brush to prevent the latter from turning, and means for operating the said presser-arm, substantially as described.

In testimony whereof I affix my signature in presence of two witnesses.

EDWARD B. JACOBSON.
